UNITED STATES PATENT OFFICE.

JOSEPH LEHNBEUTER, OF ST. LOUIS, MISSOURI, ASSIGNOR TO THE CLAES & LEHNBEUTER MANUFACTURING COMPANY, OF SAME PLACE.

SHOW-CASE.

SPECIFICATION forming part of Letters Patent No. 638,253, dated December 5, 1899.

Application filed August 21, 1899. Serial No. 728,002. (No model.)

To all whom it may concern:

Be it known that I, JOSEPH LEHNBEUTER, a citizen of the United States, residing at St. Louis, State of Missouri, have invented certain new and useful Improvements in Show-Cases, of which the following is a full, clear, and exact description, reference being had to the accompanying drawings, forming a part hereof.

10 My invention has relation to improvements in show-cases; and it consists in the novel construction of details more fully set forth in the specification and pointed out in the claims.

In the drawings, Figure 1 is a top plan view 15 of a glass case with top wall partly broken away and the end and longitudinal walls in section, taken in a plane indicated by line 1 1 of Fig. 2. Fig. 2 is a side elevation with part of one of the longitudinal walls broken away.

20 Fig. 3 is an end view of the securing-bracket enlarged. Fig. 4 is an enlarged section on line 1 1 of Fig. 2. Fig. 5 is an end view of one of the corner-brackets and screw securing the same to the top wall. Fig. 6 is a top plan view of the corner-bracket, and Fig. 7 is a sectional detail showing the cushioning plug or sleeve encircling the shank of the securing-screw.

The object of my invention is to provide 30 glass show-cases with a wall-fastening bracket which while the same is applied at the angle formed between any two walls of the case will in no way interfere with the light at the meeting edges of the walls thus fastened. By 35 thus minimizing the obstruction to the light-rays a superior finish is imparted to the edges of the show-case, as will more fully appear from a detailed description of the invention, which is as follows:

40 Referring to the drawings, 1 1 represents the longitudinal vertical walls of a glass show-case, 2 the end wall, and 3 the top wall. Distributed at the angle or meeting edges of any two walls are a series of wall-fastening brackets, each comprising two arms 4, the angle 45 between which corresponds to the angle which the glass plates constituting the walls of the case make with each other, (in the present instance a right angle.) The free end of each 50 arm 4 terminates in an expanded preferably disk-shaped bearing or base 5, whose plane

surface is adapted to bear directly against the glass plate. Each base 5 is provided with a centrally-disposed screw-threaded socket 6, which is adapted to receive the screw-threaded 55 end of the shank of a securing-screw 7, the head of the latter being provided with suitable depressions or recesses 8 for the reception of the arms of a key (not shown) by which the screw is driven home.

The meeting-point of the arms 4 is preferably expanded into a lobe 4', which in some instances may be provided with a screw-threaded opening and receive the screw-threaded end of a screw 7', which I may use as 65 an additional fastener in cases where it is desirable to connect any three plates or walls of the show-case at the corners. This additional fastener is illustrated in Figs. 2, 5, and 6.

It will be seen from the foregoing that the 70 arms of the brackets span the meeting edges or bases of the angles formed by the two walls to which the arms are secured, the span between the arms and such meeting edges permitting the free passage of light-rays and resulting in a superior finish for the case. Under 75 the old forms of construction, where an ordinary angle bar or bracket was used, with the face of each member of such angle-bar secured to the glass plate, the light was intercepted at that particular point of the meeting edges of the plates, the members of the brackets showing through the glass. The objectionable feature is wholly eliminated by 80 my present improvement.

It is to be understood, of course, that I do not limit myself to the precise shape of the arms, nor to the angle they make with one another, nor to the contour of the supporting bases or bearings, as heretofore referred to, 85 but that minor changes might be made in the device without departing from the spirit of my invention. It is obvious that the angle between the arms may range anywhere from ninety degrees (or less) to one hundred and 90 eighty degrees.

While the brackets perforated at the lobes or meeting ends of the arms are admirably adapted for corner-pieces, the same may be used, when placed in series along the upper 100 edge of the case, to support between them a rod or bar 10 (the rod being passed through

the openings of the lobes) for the support and display of novelties inside the show-case.

In order to prevent the head of the securing-screw from bearing directly against the glass plate, I insert into the opening of the glass through which the shank of the screw passes a preferably wooden plug 11, (see Fig. 7,) which normally projects beyond the surface of the glass. The screw-head thereby bears against the end of the plug, the shank of the former at the same time being prevented from rubbing against the walls of the hole formed in the glass.

Having described my invention, what I claim is—

1. A show-case bracket adapted to have its free ends secured to two meeting walls of the show-case, the body of the bracket spanning the base of the angle formed by the walls, substantially as set forth.

2. A show-case bracket comprising two arms angularly disposed toward one another, and means for securing the free ends of the arms to the two meeting walls of the case, the arms spanning the base of the angle formed by the walls, substantially as set forth.

3. A show-case bracket comprising two arms meeting at a common point and disposed at an angle corresponding to that formed by the planes of any two walls of the show-case, expanded bases at the free ends of the arms

adapted to bear against the walls of the case, screw-threaded sockets formed in the expanded bases, and securing-screws passed through suitable openings of the walls and entering the said sockets, the arms of the brackets spanning the base of the angle formed between the meeting walls whereby the light-rays are uninterrupted at the points opposite said brackets, substantially as set forth.

4. A show-case corner-bracket comprising two arms meeting at a common point, an expanded lobe formed at the point of juncture of the two arms, expanded bases at the free ends of the arms adapted to bear against the walls of the case, screw-threaded sockets formed in the expanded bases, securing-screws passed through suitable openings of the walls and entering said sockets, the arms of the bracket spanning the base of the angle formed between the walls to which the bases of the arms are secured, a screw-threaded opening formed in the lobe at the meeting-point of the arms, and a bolt passed through the wall opposite the lobe and inserted into the lobe, substantially as set forth.

In testimony whereof I affix my signature in presence of two witnesses.

JOSEPH LEHNBEUTER.
